Inventor: John McFarland,
By Thomas G. Orwig, Attorney.

UNITED STATES PATENT OFFICE.

JOHN MCFARLAND, OF DEDHAM, IOWA.

END-GATE.

SPECIFICATION forming part of Letters Patent No. 448,249, dated March 17, 1891.

Application filed August 5, 1890. Serial No. 361,145. (No model.)

To all whom it may concern:

Be it known that I, JOHN MCFARLAND, a citizen of the United States of America, and a resident of Dedham, in the county of Carroll 5 and State of Iowa, have invented an Improved Wagon-End-Gate Fastener, of which the following is a specification.

My object is to facilitate the fastening and unfastening, adjusting, and removing of a 10 wagon end-gate, adapted to be used as a gate, shoveling-board, or seat at the will of the user.

My invention consists in the construction, combination, and use of devices with a wagon-box and end-gate, as hereinafter clearly set 15 forth, pointed out in my claim, and illustrated by the accompanying drawings, in which—

Figure 1 is a side view showing my complete invention applied as required for practical use as an end-gate and the gate closed and locked. Fig. 2 is a side view showing the end-gate supported in position as required for practical use as a shoveling-board. The dotted lines in Fig. 2 represent the end-gate 25 in position for use as a seat. Fig. 3 is a perspective view showing the end-gate closed and locked. Fig. 4 is a perspective view showing a device for attaching the supporting-rope to the wagon-box and lengthening and shortening 30 the rope as required to regulate its tension.

A represents a wagon-box of common form.

A² represents the auxiliary side-boards of the wagon-box.

A³ are perforations in the rear end portions 35 of the side-boards A².

B represents the rear cross-bar to which the bottom boards of the box are fixed. This cross-bar B projects rearward past the said bottom boards and is adapted to support the 40 end-gate. The end portions of the bar B project past the sides of the box A and are made of equal width with that portion of the bar that projects rearward from the bottom board.

C represents the back, and D the side pieces, 45 of an end-gate. The back C and side pieces D are strengthened and connected by means of bars F and F², braces H, and angle-irons H², fixed thereto. The ends of the bar F extend by the sides D and are approximately 50 circular in cross-section. These projecting

ends are provided with transverse perforations adapted in size to admit a rope therein. The bars F and F² and the braces H have pins J fixed to their outer surfaces and projecting at right angles therefrom. 55

K is a hook made of flat metal and is fixed to the lower end of the side pieces D. This hook has a double-elbow-shaped bend in one end portion, the rear angle K² of which is adapted to engage the projecting end portion 60 of the bar B. A corresponding hook is applied on the opposite side, but not shown in the drawings.

L represents a rope adapted in size to pass through the perforations in the sides of the box 65 and the ends of the bar F. The device shown in Fig. 4 consists of an angle-plate M, made of metal and perforated in each end portion. This angle-plate also has semicircular notches in the parallel edges of one end portion thereof. 70

In the practical use of my invention I place the end-gate in a vertical position, so that the lower end of the end-gate will be supported by the bar B, and the angle K² of the hook K engage the projecting ends of the bar B, and 75 the weight of the sides D will hold the end-gate in a vertical position when the box is empty and stationary. I then insert the ends of the rope through the perforations in the projecting ends of the bar F, and thence 80 through the perforations A³ to the inside of the box A. I thus pass each end of the rope through the perforations in the angle-plate, as shown in Fig. 4, thence obliquely across the under side of the said angle-plate, thence 85 upward, so that the rope engages one of the notches in the edge of the plate, thence across the top of the plate beneath the rope and allow the end to depend from the opposite edge of the plate, as shown clearly in 90 Figs. 3 and 4. I then loop the bight of the rope around one or both of the projecting ends of the bar F and then place the bight of the rope under the lower pair of pins J. If I desire to still further tighten the rope, I 95 place it in engagement with one or both of the upper pair of pins J.

When I desire to use the end-gate as a shoveling-board, I remove the bight of the rope from engagement with the pins J and 100

tilt the end-gate backward and allow it to be supported by the rope. I adjust the end-gate to any angle by simply looping the rope over the projecting ends of the bar F any desired 5 number of times.

I claim as my invention—

A wagon end-gate having a bar fixed to its rear side and the ends of the bar perforated, and fixed pins projecting outward below the

bar, and a rope passed through the perforated ends of the bar and its ends fastened to the sides of the wagon-box, to operate in the manner set forth, for the purposes stated.

JOHN McFARLAND.
